UNITED STATES PATENT OFFICE.

HERMAN W. LANDWEHR, OF HOLLAND, MICHIGAN.

WASHING MACHINE.

Application filed August 10, 1925. Serial No. 49,190.

To all whom it may concern:

Be it known that I, HERMAN W. LANDWEHR, a citizen of the United States of America, residing at Holland, in the county 5 of Ottawa and State of Michigan, have invented certain new and useful Improvements in Washing Machines; and I do hereby declare the following to be a full, clear, and exact description of the invention, such as will 10 enable others skilled in the art to which it appertains to make and use the same.

This invention relates to washing machines, being particularly concerned with machines of this character of the barrel type 15 or cylinder type wherein there is provided a cylinder mounted for oscillation about its longitudinal axis, the clothes being placed in said cylinder and subjected to the action of the washing fluid of water and soap or 20 other similar material. Machines of this character usually have the cylinder mounted to turn or oscillate about a horizontal axis, the cylinder being mounted within an outer container which holds the water. Such containers 25 require cleaning and it is usually necessary to remove the cylinder for this purpose, the same being heavy and cumbersome to lift, and usually wet and unhandy to remove at the time the removal is desired.

30 One primary object and purpose of the present invention is to make a clothes holding cylinder for washing machines which includes an open frame, which is completed in cylindrical form by the addition of readily 35 connected or detached segments, which when removed, as they may be separately and independently, leaves the open frame which may be easily reached through to clean out the container at the bottom thereof. A further 40 object of the invention is to make the frame with cross bars therein which lie lengthwise of the cylinder and which have inwardly projecting flanges serving as baffles for the washing machine cylinder, in 45 practice these bars being formed from commercial T bars, the inwardly extending leg or flange of the T providing the baffle, associated with each bar. Various other objects 50 and purposes will appear as understanding of the invention is had from the following description, taken in connection with the accompanying drawing, in which,

Fig. 1 is a vertical cross section through the washing machine with the complete cylinder of my invention therein.

Fig. 2 is a like section, the segmental cylinder walls being removed.

Fig. 3 is a perspective view of the cylinder frame, and

Fig. 4 is a perspective view of one of the 60 segmental wall sections of the cylinder.

Like reference characters refer to like parts in the different figures of the drawing.

In the washing machine, there is an outer container, indicated at 1, having an open 65 upper side, the same forming no novel part of the present invention. Within this container the cylinder is mounted for oscillatory movements about a horizontal axis. In the construction of the cylinder, a frame is 70 provided including two spaced apart end members 2 and 3, each having approximately the shape of an equilateral triangle, the corresponding apices of which are connected by T bars 4 having their legs or flanges 4^a 75 extending inwardly. These bars 4, three in number are permanently connected at their ends to the end members 2 and 3 in any suitable manner.

The cylinder is completed by the addition 80 of three sections which may be detachably connected to the frame described. Each of said sections comprises two end members 5 spaced apart the same distance that the ends 2 and 3 of the frame are spaced, each being 85 substantially the segment of a circle in outline and having a length at its straight side substantially equal to the length of one side of an end member 2 or 3 of said frame. The members 5 are connected together at their 90 ends by bars 6 and 7 and other flat bars 8 are disposed between the said members 5 adjacent their outer curved edges and connected thereto, the members 5 preferably having openings to receive the ends of the bars 8. 95 Bars 8 are provided with a plurality of openings therethrough, shown as located lengthwise of said bars. Each of the bars 6 has two spaced apart hooks 9 formed integral therewith, being adapted to pass under the adjacent edge of a frame bar 4 when the section is applied to the frame, the straight sides of the segment ends 5 lying against the outer edges of the frame ends 2 and 3. Turn buttons 10 are mounted on the bars 4 100 and are adapted to be turned over the bars 7 of the sections thereby detachably securing the said sections in place. When all of said cylinder sections are connected to the frame and in place, a complete cylinder is 105 110

provided, and clothes may be placed in said cylinder by removing any one of the sections, on release of the turn buttons 10 associated therewith, said section, as well as 5 the other sections being formed with outward turned lips 11 at the outer edges of the ends 5 for ready engagement by the hands so that a section may be lifted away from the frame.

The washing action is the same in this 10 machine as in any cylinder type oscillation washing machine, baffles being provided by the inwardly extending flanges or legs 4^a of the bars 4. When it is desired to clean the machine, the water may be 15 drained from the container 1 by opening the valve at 12 at the lower part of the container. The segmental sections mounted on the frame of the cylinder are released and removed, the open frame left being easily 20 worked through to complete the cleaning and washing out of the container. Each section is comparatively light and easy to detach and remove or replace. And when 25 removed the open frame left does not interpose any obstacle to the access to the bottom of the container 1 in which it is mounted.

This construction of cylinder for washing 30 machines is very practical and useful and has proved its value in actual practice. Various changes in minor detail of construction may be resorted to without departing from the invention defined in the claims appended hereto, and it is to be considered 35 that the invention comprehends all such changes in structure that come within the said claims.

I claim:

1. In a washing machine, a cylinder including an open frame having two spaced apart end members of triangular shape, bars connecting the end members at the apices of the triangles, and cylinder segments each comprising two ends each having a straight edge and an edge curved in the arc of a circle and bars connecting the ends, said cylinder segments being located with said straight edges of their ends against the edges of the end members of the frame, and 45 means for detachably connecting said cylinder segments to said frame, substantially as described.

2. A washing machine cylinder comprising, an open frame having two spaced apart 50 end members of polygonal shape, bars connecting said end members, said bars being located at the corners of said end members, a plurality of cylinder segments one for each 55 edge of the end members, each comprising the two ends shaped substantially as the segment of a circle, bars connecting said ends and located adjacent the outer curved edges thereof, said cylinder segments being located with their ends against the edges of 60 said frame end members, and means for de-

tachably connecting the cylinder segments to the frame, substantially as described.

3. A washing machine cylinder comprising, an open frame having spaced apart end members, bars connecting the end members in spaced apart relation, each of said bars being T-shaped in cross section and having a flange extending inwardly, and cylinder segments detachably connected to the frame, each of said segments comprising two spaced apart ends, and bars connecting the ends and located adjacent the outer edges of said ends, substantially as described.

4. A washing machine cylinder comprising, an open frame having spaced apart end members of polygonal shape, bars connecting the end members at the corners thereof, a plurality of cylinder segments each comprising two ends formed in the shape of a segment of a circle and spaced perforated bars connecting said ends and located adjacent the curved outer edges of the ends, and means for detachably connecting said cylinder segments to said frame to form a complete enclosed cylinder.

5. A washing machine cylinder comprising, an open frame having spaced apart ends of polygonal shape, a plurality of bars connecting said ends and located at spaced distances from each other, a plurality of cylinder segments each comprising two spaced apart ends, two spaced apart bars connecting the ends, and a plurality of perforated bars located between the ends adjacent the outer edges thereof, hook members extending from one of said first mentioned bars on each of the segments, and means movably mounted on each of the frame bars to engage over the other of said first mentioned bars of said cylinder segments whereby when said hook members are engaged under an adjacent bar of the frame said cylinder segment is securely yet detachably connected to the open frame.

6. A washing machine cylinder comprising, an open frame having spaced apart end members substantially in the shape of an equilateral triangle, bars connecting the end members, said bars being T-shaped in cross section and having inwardly extending flanges, three cylinder segments each comprising two spaced apart ends having the shape of the segment of a circle, and bars connecting said ends located adjacent the outer curved edges thereof, the straight edges of said ends being adapted to engage against the edges of the frame end members, and interengaging means on said cylinder segments and on the frame bars for detachably connecting said cylinder segments to the frame.

In testimony whereof I affix my signature.

HERMAN W. LANDWEHR.
